COMBINED TYPEWRITING AND COMPUTING MACHINE

Otto Thieme, Hartford, Conn., assignor, by mesne assignments, to Underwood Elliott Fisher Company, New York, N. Y., a corporation of Delaware

Application September 16, 1931, Serial No. 563,033

5 Claims. (Cl. 235—60)

This invention relates to the indexing mechanism of combined adding and typewriting machines, in which the type-keys set up indexing devices preparatory to adding the amount that is typed. The invention presents an improvement upon the indexing mechanism disclosed in the patent to Hanson, 1,416,464, of May 16, 1922.

An object of the invention is to compact the mechanism, the indexing or pin-carrying bar occupying less space widthwise of the machine. A further object is to simplify the parts and reduce the cost of manufacture, as well as to improve the operation of the mechanism, and to render it more responsive, reliable and durable.

In said patent, vertical cylindrical holes are drilled in a row through the indexing bar from top to bottom, and index-pins are set in these holes, a returning spring being coiled around each pin. On the side of the patented bar is fastened an overhanging plate, which enters notches that are cut in the pins, to prevent them from rotating; and said plate also serves as top and bottom stops. A universal spring-pressed latch-plate holds the pins in normal and depressed positions. The latch-plate can be cammed to one side by any descending pin, so as to release any pin that is already depressed.

According to the present improvements, the indexing bar (usually formed with a register-driving rack and other appurtenances) is in the form of a plate stamped from sheet-metal, and the index-pins are placed in a rack that is secured against the side of the indexing bar. This rack has a horizontal groove or main channel of rectangular contour cut in one side for its entire length; and it also has spaced vertical rectangular cuts each open at top and bottom. Each index-pin is simply cut from sheet-metal, and is flat, and fits in one of the rectangular cross-cuts, by which it is guided, and also crosses or descends through the main channel in the rack, and is encased by the rack against the side of the indexing bar.

Each pin is formed with a shoulder, which is normally pressed up by a spring against the top flange of the rack. This shoulder also engages the lower flange of the rack at the down stroke of the pin.

The returning springs of the pins are simple helices, which are dropped into the channel between the pins, the space between the pins being just sufficient to house the spring. There is formed on each pin a finger or bearer that overtops the spring, and the latter, by pressing up against this bearer, returns the pin to nor-

mal position, the pin being arrested by engagement of the bearer with the top flange of the rack. Assembling is very inexpensive, since the pins and springs may be readily made and placed in the grooves in the channeled rack, and the latter may be fastened to the side of the indexing bar.

Upon said rack is hinged a latch, in the form of a sheet-metal plate having ears at its ends which are pivoted to the ends of the rack. The latch has a top inturned flange, which serves as a universal detent for the pins, and engages grooves in the sides of the pins. A spring holds the latch in normal position. When any pin is depressed, it forces the universal latch to one side, thereby releasing the formerly set pin. Upon completion of the depression of any pin, it is held depressed by the latch-bar, which enters another notch therein.

The pins are flat and thin, and the rack is also thin, and the indexing bar that supports it is also very thin, so that these devices can be compactly mounted side by side in the machine, as required. The springs move freely in their confinement, and have no opportunity to bind or to function improperly. The liability of clogging by dust, etc., is minimized or overcome.

Other features and advantages will hereinafter appear.

In the accompanying drawing,

Figure 1 is a fragmentary enlarged perspective to illustrate the normal construction and operation of the indexing bar.

Figure 2 is a longitudinal elevation of an indexing bar having the present improvements embodied therein.

Figure 3 is a perspective sectional view, showing index-pins in different positions, and illustrating the operation of the universal latch.

Figure 4 is a perspective showing the parts separated.

Figure 5 shows an Underwood combined typewriting and computing machine embodied in the present improvements.

Figure 6 is an enlarged view of the novel index-pin.

As usual, keys 10 operate numeral-types 11 that strike upon a platen 12 on a carriage 13, which is fed by an escapement-mechanism 14, 15, and also carries a dog 16 having a tooth 16a to operate jacks 17. These jacks depress rods 18, each of which vibrates a lever 19 and operates a bell-crank 20 to set forwardly an indexing bar 21. This indexing bar has a longitudinal row of indexing pins 22, which are advanced sufficiently to bring them beneath key-operated pin-depress-

ing bars 23, which extend across the machine and form portions of linkages 24, the latter being operable as usual by means of pins 25 pendent from the numeral-keys 10. After the indexing of the pins 22 by the keys, the indexing bars 21 are advanced by general operator 26, so that their racks 27 operate dial-pinions 28.

The indexing pins 22 form a row extending longitudinally of the indexing bar 21, and are 10 encased between said bar and a rack 29. The rack is illustrated as a plate that is held against the side of the indexing bar 21 by means of rivets 30, the upstanding pins being confined by and loosely fitting between the rack 29 and the 15 plate-like body of the indexing bar 21.

The pins normally project up above the casing, but upon depression of the key its cross-bar 23 will press down a pin, causing it to project below the casing. The upper and lower 20 pin-positions are shown at Figures 1, 2 and 3.

It is desired to hold the pin in its set position, as in the case of the right-hand pin at Figure 2; and for this purpose there is employed a latch 31, which is in the form of a flange formed upon 25 a plate 32 extending along the rack and having ears 33 through which extend pintles 34, whereby the latch is hinged upon the ends of the rack 29. Compression-springs 35 are housed in the rack and press outwardly against the body 32 of 30 the universal latch, at points thereof below the ears 33, so as to press the flange or tooth portion 31 of the latch inwardly against the index-pins 22. Hence, when any pin is depressed, the latch will snap into a notch 36 that is formed 35 at the top of the pin 22. One pin is depressed upon each of the indexing bars 21, preparatory to running the number into the dial-wheels.

When a wrong pin is depressed, it is only necessary to set the typewriter-carriage back one 40 step, and then strike the correct key, which will depress the correct pin, and will further operate to restore to normal position the incorrect pin. As the correct pin is thrust down, a cam 37 thereon will cam the latch 31 away from the rack, and 45 thereby release the previously-set index-pin 22, which is at once snapped up by its returning spring 38 to normal position; while the latch 31 snaps into notch 36 of the correct pin and holds it down.

50 The cam 37 forms the upper face of a notch 39 that is formed in each pin just below the notch 36. The notches 39 are normally occupied by the universal latch 31, but, upon depressing any pin, the cam 37 forces the entire latch to one 55 side, and as soon as the pin is depressed, the springs 35 snap the latch into the upper notch 36 to lock the pin down, the latch also re-entering the lower notches in the remaining pins.

The rack 29, with its set of index-pins 60 encased between the rack and the face of the indexing bar 21, presents a light, compact and inexpensive construction, inasmuch as the rack may be produced by simply forming a channel 65 40 for the length of the bar, the shallowness of the channel matching the thickness of the pins 22, so that the latter will fill the space or fit between the broad side of the channel and the side of the indexing bar 21.

The rack may be formed with vertical channels 41 of the same shallowness or depth as the main channel 40, each vertical channel continuing through the upper and lower flanges 42 and 43 which are produced by forming the channel 40. The depth of each vertical or cross channel 75 41 matches that of the main channel 40, and

the width of the vertical channel 41 is equal to the width of the pin 22; thus when the rack is fastened to the side of the indexing bar, it is found that all of the pins are securely mounted and guided, while the necessity of individual fastenings for the pins is avoided.

A further feature is that one pin may co-operate with the next pin to form a housing for its pin-spring 38. Each pin is provided with a stop-shoulder 44, which arrests the depression of the pin by engaging with the lower flange 43; and the spring 38 is dropped in between the stop-shoulder and the side of the adjacent pin. There is no need of individual fastenings for the springs, as they are closely housed or confined 15 by the adjacent pins, and by the top and bottom flanges 42, 43, as well as by the walls 29 and 21 of the casing. Therefore all of the moving parts in the set are mounted by means of the two members 29, 21, which are universal thereto, thus securing cheapness and compactness.

Included in this set of pins is a zero-pin 45, which is depressible by a cross-bar 45a, which is operated by the zero-key, and is also depressible by a lever 46, which is pivoted at 47 upon the indexing bar 21. At the conclusion of the operation of the general operator 26, a universal bar 48 rises and lifts all of the depressed levers 46, thereby depressing their zero-pins 45 and releasing the latches 31, so that all depressed index-pins are returned by their springs to normal positions. The zero-pin 45 has a cutout 49, which serves as a bearing for the rear end of the lever 46, which plays between the indexing bar 21 and the rack 29.

All of the pins are supplied with upper stops 50 for arresting the up strokes of the pins. These stop-pins contact with the upper flange 42; and said stops are broadened so as to form bearers for the compression-springs 38. The last rear compression-spring is guided between its pin and a 40 filler-block 51, which is placed in the channel 40 and fastened by the rivets 30. A similar filler-block 52 may be used in the other end of the channel 40.

The Hanson guide-plate is eliminated in the present invention, which prevented the round pins from turning. The round pins had to be milled on two sides, at considerable expense, as great care had to be taken in getting them properly located for the cutters. In the present invention flat pins are used which are cheap to manufacture, as they may be punched and then smoothed down on the side where the projecting ledges are, to make a perfect fit. The sides adjacent the projecting ledges are provided with milled grooves, and the pins being flat are easily located for the millers, and ten or more of these pins can be milled at one operation.

The guide-holes for said Hanson round pins 60 must be all individually drilled twice, as said holes were made of two different diameters. These holes were also separately reamed for each Hanson pin. It was very hard to get these holes in the exact position, and they might therefore vary 65 four thousandths of an inch or more. In the present invention the bed or holding member is open on one side and utilizes the indexing bar for closing said opening when the bed is attached. The bed or rack may be put in the milling machine, and all the guideways for the ten pins milled at one run of the milling machine, and in this manner a perfect alignment, that is correct within one thousandth of an inch in depth and pitch, can be cheaply obtained for said pins.

The springs in said Hanson patent had to be wound quite accurately, as they must fit just freely over said pins and must not be too small or too large; otherwise they would cause binding.

5 In the present invention the springs do not have to be accurately wound, as they do not embrace any part of the pin-mechanism.

Furthermore advantage is taken of every bit of space between said pins, and they are provided 10 with extensions, the upper extension acting as a stop, and also providing means whereby the springs may bear against said pins to return them to their normal position. In the present invention, the assembly of the complete indexing bar 15 is made very simple and cheap.

The pins have a very light touch, and are condensed and the milling of these flat pins is much easier than that of a round pin, besides being 20 much more accurate. The rack or bed-plate can be made more cheaply and quickly, and more accurately, the pins can be made much more cheaply and the returning springs do not have to be accurate, and can be made cheaply, and the whole indexing bar can be assembled rapidly and easily, 25 and forms a condensed and accurately operating pin-bar.

The latching plate is beveled on its under side, and the lower edge of the top slot in the pin is rounded to cooperate with the round portion of 30 said latching plate, to insure a locked pin being restored when said locking plate is swung out by another pin being depressed. These two rounded corners insure the pin being released and passing said plate, and not being caught on 35 any sharp corners, which is a valuable feature of the present invention.

At Figure 6 the opening of the upper notch 36 of the index-pin is broadly rounded at 53 on the lower face. This permits the latching tooth 31 40 to be pressed inwardly by its springs 35 before the completion of the down stroke of the pin, thus avoiding danger of the latch failing to hold the pin down, as might otherwise occur.

For further insuring the snapping of the latch 45 31 into the upper notch, the indexing bars 23 are made to impart to the pins excessive downward motions. This lost or excessive motion gives time for the latch 31 to swing all the way into the notch. The clearance between the shoulder and 50 the lower flange of the rack is seen at 54, Figure 3.

Variations may be resorted to within the scope of the invention, and portions of the improvements may be used without others.

55 Having thus described my invention, I claim:

1. In combination, an indexing bar, a set of sliding index-pins therefor, a rack for mounting said index-pins, and means securing the rack to the side of the indexing bar; said rack having a 60 horizontal longitudinal groove in one side, and having flanges above and below said groove, said flanges having spaced vertical guiding-cuts which open at top and bottom, in which the pins fit, the pins occupying said groove, and each pin extending above the upper flange and having notches therein, each pin also having abutments projecting from one side of each pin into the groove between the flanges; said bar serving to confine the pins in the rack, each abutment engageable 65 respectively with a top or bottom flange, to serve as a stop, a universal plate having ears at either end and pivots connecting said ears to said rack, said plate having a latching flange cooperative

with said notches to hold said pins in set position.

2. In combination, an indexing bar, a set of sliding index-pins therefor, a rack for mounting said index-pins, and means securing the rack to the side of the indexing bar; said rack having a 5 horizontal longitudinal groove in one side, and having flanges above and below said groove, said flanges having spaced vertical guiding-cuts which open at top and bottom, in which the pins fit, the pins occupying said groove, and each pin extending above the upper flange and having notches therein, each pin also having abutments projecting from the pins into the groove; said bar serving to confine the pins in the rack, the abutments being engageable respectively with a top or bottom flange, to serve as upper and lower stops, a universal plate having a latching flange and ears, and pivots on said rack, springs embedded in said 10 rack below said pivots to force said latching flange into contact with said notches to hold said pins.

3. In combination, an indexing bar, a set of sliding index-pins therefor, a rack for mounting said index-pins, and means securing the rack to the side of the indexing bar; said rack having a horizontal longitudinal groove in one side, and having flanges above and below said groove, said flanges having spaced vertical guiding-cuts which open at top and bottom, each index-pin 15 fitting in one of the vertical cuts and extending above said upper flange and having notches therein, the pins being encased between the rack and the side of the indexing bar, each pin being flat and formed with two flange-engaging projections to serve as stops, and having a returning spring which presses up beneath one of said projections, the pins, projections and springs occupying said groove, a universal plate having a latching flange pivoted to said rack, springs embedded in said rack and pressing on said plate 20 to force said latching flange into said notches.

4. An indexing bar and pins settable therein, said bar having a longitudinally extended groove with upper and lower flanges, said flanges having therethrough spaced upper and lower guiding cuts, said pins lying in said cuts and extending beyond said upper flange, and having notches in said pins above said upper flange, a spring-pressed universal plate having a latching flange 25 cooperative with said notches above said upper flange to temporarily hold said pins in set positions, each of said pins also having a stop shoulder cooperative with said lower flange to limit its downward movement and a side projection extending in the same direction but beyond said stop shoulder, and a spring in said groove 30 below each projection and adjacent each stop shoulder, said springs all seated on said lower flange.

5. An indexing bar having upper and lower flanges with transverse notches therein, pins in the notches each having a side projection with upper and lower stop portions, the lower stop portion being cooperative with said lower flange to stop downward movement of a pin and the upper stop portion being cooperative with the upper flange and extending laterally beyond the lower stop portion, and a spring seated on the lower flange adjacent each lower stop portion and beneath an upper stop portion.

OTTO THIEME.
